CLAIM

The ornamental design for an orthopedic pin, as shown.

DESCRIPTION

FIG. 1 is a top plan view of the orthopedic pin showing my new design;

FIG. 2 is a side elevational view thereof;

FIG. 3 is a bottom plan view thereof;

FIG. 4 is a side elevational view thereof taken at 90° from the view of FIG. 2;

FIG. 5 is a side elevational view thereof taken at 90° in the other direction from FIG. 2; and

FIG. 6 is a side elevational view thereof taken at 180°, or on the opposite side, from the view of FIG. 2.
